UNITED STATES PATENT OFFICE.

JAMES M. ARENDALE, OF BIRMINGHAM, ALABAMA.

SAFETY DEVICE FOR CROSSINGS.

Application filed May 19, 1923. Serial No. 640,220.

To all whom it may concern:

Be it known that I, JAMES M. ARENDALE, a citizen of the United States, residing at Birmingham, in the county of Jefferson and 5 State of Alabama, have invented new and useful Improvements in Safety Devices for Crossings, of which the following is a specification.

An object of this invention is to produce 10 a safety device for railway crossings in the nature of a revolvable member arranged transversely of a roadway at the opposite sides of a railroad revolved in the direction of approach of a vehicle or pedestrian toward the railroad to cause a backward movement to be imparted to either the vehicle or pedestrian, said means being operated on the approach of a train in either direction from the crossing.

20 A further object is to produce a safety device for railway crossings in which the roadway is elevated for a considerable distance at the opposite sides of the crossing, and to arrange in the walls provided at the 25 ends of the elevations roller members which are normally closed by heavy metal coverings so that a vehicle or pedestrian may readily travel thereover, means in the nature of a semaphore operated by the electric 30 block system of the railway by a train approaching the crossing from either direction swinging the semaphore to danger position and likewise swinging the covers to open position, while means, actuated by the same 35 source is provided for revolving the rollers in a direction away from the crossing, so that both a stationary and a revolving obstruction is provided for persons or vehicles moving in the direction of the crossing when 40 a train approaches the crossing.

To the attainment of the foregoing and other objects which will present themselves as the nature of the invention is better understood, reference is to be had to the drawings which accompany and which form part 45 of this application.

In the drawings:—

Figure 1 is a plan view of a railway crossing illustrating the application of the improvement, on the roadway thereof.

Figure 2 is a transverse vertical detail sectional view approximately on the line 2—2 of Figure 1.

Figure 3 is a longitudinal vertical sectional view, in detail showing the semaphore

arm thrown to danger position and the cover for the roller raised thereby.

Figure 4 is a transverse vertical sectional view on the line 4—4 of Figure 1 and in detail.

Figure 5 is a view illustrating the electric wiring.

The rails of a railway track are indicated in the drawings by the numeral 1 and the roadway which traverses the track is indicated by the numeral 2. The roadway for a suitable distance from both sides of the track 1 is elevated, as at 3 and the said roadway, at this portion thereof, is excavated to provide a round transverse depression therefor. In this depression there is arranged a metal pipe segment 4, one of the ends of which being level with the roadway proper and the other end terminating with the elevated portion 3. The casing 4 preferably has closed ends 5 provided with bearing openings for anti-frictional bearings 6 that receive therethrough a shaft 7 that passes centrally through a roller 8. Each of the rollers 8 may be and preferably 75 has its outer surface corrugated longitudinally and also the rollers are preferably hollow but are constructed of hardened material, such as metal.

On the elevated end 9 of the casing 4 there 85 is hinged, as at 10 a cross sectionally concavo-convex cover 11 for the rollers 8. The covers 4 are also constructed of some light but strong metal, the said covers serving as an inclined plane over which travel vehicles 90 or pedestrians when moving in the direction of the crossing.

To one side of each of the rollers 8 there is arranged a post 12, each of the said posts carrying a semaphore or pivoted signal arm 95 13, and a rod 14 is loosely connected between the semaphore and the cover 11. When the semaphore is swung to danger position, the cover 11 will be swung to open position with respect to the roller, and 100 in addition to said roller serves as an obstructing element for persons or vehicles approaching the crossing.

The rollers 11 are revolved by an electrically operated motor 14' which is suitably 105 housed, the shaft of the motor having sprocket wheels thereon around which are trained sprocket chains 15 that are likewise trained around sprocket wheels on the shaft 7 of the rollers 8. The sprocket wheels are 110

so arranged as to cause the turning of the rollers 8 in a direction away from the crossing. The motor is in circuit with a source of electricity which, of course, includes a 5 battery, and the conductors of which being connected to the rails of the track 1. In the circuit there is a circuit maker 16 which is really in the nature of a switch, and which is thrown to make the circuit when the 10 wheels 17 of a car 18 approach the crossing from either direction completes the circuit.

It is thought that the foregoing description, when taken in connection with the 15 drawings will fully set forth the construction and advantages of the improvement to those skilled in the art to which such inventions relate.

It is to be understood that while I have 20 herein set forth a satisfactory embodiment of the invention as it now appears to me, I hold myself entitled to make such changes therefrom as fall within the scope of what I claim.

Having described the invention, I 25 claim:—

1. A safety device for railway crossings, comprising rollers arranged transversely of the roadway at the opposite sides of the crossing over which traffic normally passes, 30 and means actuated by a train approaching the crossing, for revolving the rollers in a direction away from the crossing.

2. A traffic obstructing means for railway 35 crossings when a train approaches the crossing, and in which the roadway, at a suitable distance from the crossing is elevated, of rollers arranged at the terminal of said elevated portions of the railway, and means, actuated by a train approaching the crossing 40 for revolving the rollers in a direction away from the crossing.

3. In a traffic obstructing means for railway crossings, in which the roadway is raised for a suitable distance at the sides 45 of the crossing, of corrugated rollers journaled at the ends of the said raised portion of the roadway and over which the traffic normally passes, of means actuated by a train approaching the crossing for revolving the rollers in a direction away from 50 the crossing.

4. A traffic obstructing means for railway crossings, in which the roadway is raised at and adjacent to the crossing, comprising corrugated rollers journaled in 55 bearings at the termination of the raised portions of the roadway, segmental covers therefor over which the traffic passes, and means actuated by a train approaching the crossing for raising the covers and for revolving the rollers in a direction away from 60 the crossing.

5. A traffic obstructing means for railway crossings in which the roadway is raised for a suitable distance from the sides 65 of the crossing and in which said crossing at the terminal of the raised portions is concaved transversely, of segmental tubular casings arranged in the said concavities, a longitudinally grooved roller in each of the 70 casings, anti-frictional bearings for the rollers, segmental covers hinged to the elevated end of the casing designed to be normally swung over the rollers and provide a plane for the passage of traffic, and means 75 actuated by a train approaching the crossing for raising the covers to horizontal position and for revolving the rollers in a direction away from the crossing.

In testimony whereof I affix my signature.

JAMES M. ARENDALE.
